CLAIM

The ornamental design for a serving tray, substantially as shown and described.

DESCRIPTION

FIG. 1 is a top plan view of a first embodiment of a serving tray showing my new design;

FIG. 2 is a bottom plan view thereof;

FIG. 3 is a side elevational view thereof;

FIG. 4 is a sectional view thereof taken along the line 4—4 of FIG. 1;

FIG. 5 is a perspective view thereof; and

FIG. 6 is a perspective view of a second embodiment thereof.

The second embodiment is identical to the embodiment of FIGS. 1—5 except for the raised central portion of the upper surface which is fully disclosed in Fig. 6.

Zig. 1.

Zig-Zag
